L. E. NEBERGALL

BLOCK AND ELEVATOR CONNECTER

Filed Aug. 22, 1924

Inventor:

L. E. NEBERGALL

R. J. Honomichl.

By *David O. Russell*,
Attorney

UNITED STATES PATENT OFFICE.

LORAN E. NEBERGALL, OF DENVER, COLORADO.

BLOCK AND ELEVATOR CONNECTER.

Application filed August 22, 1924. Serial No. 733,637.

To all whom it may concern:

Be it known that I, LORAN E. NEBERGALL, a citizen of the United States, residing in the city and county of Denver, State of Colorado, have invented certain new and useful Improvements in Block and Elevator Connecters, of which the following is a specification.

My invention relates to tools and apparatus employed in drilling oil, artesian and other deep wells, and especially to appliances for raising and lowering tubing, casing, and drill-pipe for such wells. It is the object of my invention to provide a strong, 10 light-weight, efficient and easily operated means for connecting casing-elevators to the tackle-blocks by which the well-casing, tubing or drive-pipe is lifted and lowered into the well. The device provided by my invention obviates the use of casing-hooks, such as have been heretofore employed for connecting the casing-elevators and blocks, and 15 enables the use of elevators having straight links in which the strength of the material is fully utilized, instead of links bent laterally at the upper portions to adapt them for 20 connection with hooks. My invention further provides a means for connecting blocks and elevators, in which the connection has 25 greater lateral flexibility than is provided by ordinary casing-hooks, and thereby facilitating the lifting of the casing from horizontal to vertical position. My invention further provides a swivelled and limitedly 30 yielding means for connecting casing-blocks and elevators.

A structure embodying my invention is illustrated in the accompanying drawings, in which Fig. 1 is a side view of the connector, with its associated elevator and 40 tackle-block, Fig. 2 is a vertical or axial section of the connector, Fig. 3 is a plan view of the same, and Fig. 4 is a detail section on the line 4—4 of Fig. 1.

Referring to the assemblage of parts shown in Fig. 1, there is represented at the lower part of the figure a casing-elevator of ordinary construction, comprising a collar 10 consisting of parts hinged together so 45 that the collar may be opened and placed around the casing 11 below the coupling 12 at the end thereof; said collar having laterally extending lugs 13 to which the links 14 are pivotally and detachably connected. 50 At the upper part of the figure is represented the lower block 15 of the elevator tackle,

said block having at the lower end thereof a detachable clevis 16, to which ordinarily is attached the eye of the casing-hook, the hook being engaged with the upper ends 60 of the elevator-links which are bent laterally inward from the planes of the lower portions thereof, to enable both links to be engaged with the hook.

In my improved connector I provide a 65 cylindrical shaft or stem 17 having formed integrally with the upper end thereof a head 18 and an eye 19, the latter preferably being vertically elongated to facilitate the passing through it of the end of the 70 clevis 16 when the connector is attached to the block. The lower end of the stem 17 is threaded and upon said threaded portion is screwed the nut 20. A cylindrical sleeve 21 is set in a groove at the upper 75 side of the nut, said sleeve being concentric with and spaced from the stem. Within said sleeve 21 and disposed loosely about the stem is a coil spring 22 which extends normally above the upper end of the 80 sleeve, as shown. About the stem at the upper end of the spring is disposed a thrust-bearing consisting of the balls 23 and the lower and upper race-plates 24 and 25. Supported upon said thrust-bearing and 85 fitting revolvably about the stem is the yoke or swivel-block which comprises a central hub-portion 26 and oppositely disposed laterally extending lugs 27, said lugs having the link-grooves 28 formed therein at their 90 upper sides adjoining their inner ends. The sectional form of the lugs in the vertical plane of the link-grooves is substantially cylindrical, as shown in Fig. 4, but the outer ends are U-shaped, the flat upper sides 95 thereof being in the horizontal plane of the upper end of the central portion 26. Resting upon the upper side of the yoke, and fitting pivotally about the stem, is the keeper-plate 29, of which the form in plan 100 is the same as that of the yoke, so that when the laterally extending portions of the plate are vertically aligned with the lugs 27 the plate extends across the upper portions of the link-grooves and prevents disengagement of the links therefrom. The keeper-plate and yoke are held normally in the locked or registering position, by means of the locking-links 30, of which the 105 upper portions are pivotally connected with the ends of the keeper-plate, and the lower portions normally extend about the U-shaped 110

outer ends of the yoke-lugs, as shown. By swinging the locking-links outwardly, as shown by dotted lines at the left of Fig. 2, the keeper-plate is released and may be 5 swung about the axis of the stem to a release position at right angles to the normal or locking position, and in said release position of the keeper-plate the link-grooves are uncovered thereby, so that the 10 elevator-links may be removed from the grooves or placed therein.

In the use of my improved connector, the same is first secured to the tackle-block by removing the clevis 16 from the block, passing the clevis through the eye 19 of the connector, and again attaching the clevis to the block, so that the connector is suspended therefrom as shown in Fig. 1. The elevator is connected with the casing, tubing or drive-pipe in the usual manner, and the connector is lowered into proximity to the elevator, the keeper-plate 29 being unlocked by raising the links 30, and said plate 15 swung about the stem to the release position at which the link-grooves 28 are open to receive the elevator-links. The links 14 are then swung into positions at which they straddle the lugs 27 of the connector-yoke, and the block is raised until the links 20 are seated in the link-grooves. The keeper-plate is then swung to its normal or locking position, to retain the links in the grooves, and said plate is secured against accidental displacement, by the dropping 25 of the locking-links 30 about the ends of the yoke-lugs 27. If the casing, tubing or drive-pipe to which the elevator is connected is lying in a horizontal position upon the ground, the elevator is so placed 30 thereon that the lugs 13 extend horizontally, and when the links are then engaged with the lugs 27 of the connector the latter may swing to any desired angular position relative to the links, as will be apparent from Fig. 4. In many forms of elevators the links are so attached to the collar that they may swing in planes parallel with the axis of the casing, but in other elevators the links are not so connected 35 therewith, and in such cases the lateral flexibility of the connector is particularly desirable. After the casing has been raised to vertical position, and while lowering the same into the well, or when lifting casing 40 out of a well, rotation of the suspended tubing or casing, as required for screwing together or unscrewing the couplings thereof, is permitted by the rotation of the yoke or swivel-block about the stem 17, free movement of the yoke being facilitated 45 by the antifriction bearing upon which it rests. The yieldable support of the connector-yoke, afforded by the spring 22, prevents sudden jars and excessive stresses resulting 50 therefrom, which are an important

contributive factor in the stripping of threads at couplings, especially when long and heavy strings of pipe are being supported. The length of the sleeve 21 is so proportioned that it will prevent excessive 70 compression of the spring, the bearing-member 24 seating upon the upper end of the sleeve when the spring has reached a maximum compression, and said sleeve then 75 receiving any load in excess of that required to compress the spring.

When the casing-tackle is employed for general hoisting purposes, or when used with elevators of which the links are not suited for engagement with the yoke or 80 swivel-block of my connector, the latter may be provided with extra links, such as the links 14 detached from the usual elevator, said links being engaged with the yoke-lugs 27 and extending below the lower end 85 of the stem, so that any desired connection may be formed with the lower ends of said links.

Now, having described my invention, what I claim and desire to secure by Letters 90 Patent is:

1. A block and elevator connector, comprising a cylindrical stem having a head and eye at the upper portion thereof, a yoke disposed rotatably about said stem and having laterally extending lugs provided with link-receiving grooves, and means on the lower portion of the stem for sustaining 95 said yoke.

2. A block and elevator connector, comprising a cylindrical stem having means at its upper end for connection with a tackle-block, a yoke fitting rotatably about said stem, said yoke having opposite laterally extending lugs provided at the upper sides 105 thereof with link-receiving grooves, means on the lower portion of the stem for sustaining said yoke, and means for retaining elevator-links in said grooves of the yoke-lugs.

3. A block and elevator connector, comprising a cylindrical stem, a yoke slidably and rotatably disposed upon said stem, said yoke having opposite laterally extending lugs adapted for engagement by elevator 115 links, means at the upper end of the stem for connecting the same with a tackle-block, a spring disposed about the lower portion of the stem and yieldably supporting the yoke thereon, and means at the lower 120 end of the stem for supporting said spring.

4. A block and elevator connector, comprising a stem having an integral eye formed at the upper end thereof and a nut at the lower end thereof, a yoke rotatably and slidably disposed about said stem, opposite laterally extending link-engaging lugs on said yoke, a spring and an anti-friction thrust-bearing disposed about the stem 125 between the nut and the yoke, and a sleeve 130

carried by the nut and engageable with said bearing to limit compression of the spring.

5. In a block and elevator connector, a vertical cylindrical stem, a yoke-member swivelled upon said stem, opposite laterally extending lugs on 15 said yoke-member, said lugs having link-receiving grooves in the upper sides thereof, a keeper-plate disposed about the stem above the yoke-member and having portions adapted to register with the yoke-lugs to 20 cover said grooves, and locking-links pivoted on said keeper-plate and engageable with the outer portions of the yoke-lugs to retain the plate in register with said lugs.

10. In a connector of the class described, a

L. E. NEBERGALL.
